PRESSURE PUMP FOR TENNIS BALL CANNISTERS OR SIMILAR ARTICLE

Robert B. Dubner, 40 Dogwood Ave., and Harold Bienenfeld, 145 Dogwood Ave., both of Roslyn Harbor, N.Y. 11576

Filed May 23, 1974, Ser. No. 472,721

Term of patent 14 years

Int. Cl. D23—01

U.S. Cl. D23—15

FIG. 1

FIG. 2

FIG. 4

FIG. 5

FIG. 6

FIG. 1 is a perspective view of a pressure pump for tennis ball cannisters showing our new design, with the pump shown in the position corresponding to the unpressurized condition of the cannister;

FIG. 2 is a side elevational view thereof, with the pump shown in the position corresponding to the pressurized condition of the tennis ball cannister;

FIG. 3 is a front elevational view of FIG. 2;

FIG. 4 is a rear elevational view of FIG. 2;

FIG. 5 is a top plan view thereof; and

FIG. 6 is a bottom plan view thereof.

The broken line representation of a tennis ball cannister and tennis ball in FIG. 1 are for purposes of illustration only.

We claim:

The ornamental design for a pressure pump for tennis ball cannisters or similar article, substantially as shown and described.
